UNITED STATES PATENT OFFICE.

HENRY M. JUSTI, JR., OF PHILADELPHIA, PENNSYLVANIA.

VENTILATOR FOR AUTOMOBILES, ETC.

Application filed November 15, 1921. Serial No. 515,187.

To all whom it may concern:

Be it known that I, HENRY M. JUSTI, JR., a citizen of the United States, residing in the city and county of Philadelphia, State 5 of Pennsylvania, have invented a new and useful Ventilator for Automobiles, Etc., of which the following is a specification.

My invention consists of a ventilator for an automobile, more particularly designed 10 to cool the feet of the chauffeur or driver thereof, and furthermore, ventilate the relative portion of the body of the automobile, the same consisting of members forming a unitary article attachable to the wall of the 15 body at an opening or port therein, as will be hereinafter described.

The invention is satisfactorily illustrated in the accompanying drawing, but the important instrumentalities thereof may be 20 varied, and so it is to be understood that the invention is not limited to the specific details shown and described, as long as such variations are within the spirit or scope of the claims.

25 Figure 1 represents a perspective view of the ventilator in open condition, and a portion of an automobile to which the same is applied.

Figure 2 represents a vertical section on 30 line 2—2 Figure 1, on an enlarged scale.

Figure 3 represents a perspective view of the ventilator detached from the automobile.

Figure 4 represents a vertical section of 35 a portion of the ventilator in closed condition on a further enlarged scale.

Similar numerals of reference indicate corresponding parts in the figures. Referring to the drawings.

1 designates a portion of the body of an 40 automobile of well known construction. 2 designates a portion of a foredoor of said body, in the wall of which is the port 3 which is in the side of the foredoor, said port forming a communication for the atmosphere with the interior of the body to cause a flow of air, more particularly over 45 heated foot boards, and when closed to eliminate danger of a leak of rain, etc. over the coil box.

40 4 designates a door for the port 3, the same being adapted to be opened to a greater or less extent to adjust the volume of air desired to be admitted into the foredoor, as in Figure 2, and when desired to cover said 55 port, as in Figure 4, to prevent the admission of air, rain, etc. into the foredoor, said

door consisting of a plate of metal or other suitable material having on its upper end the series of knuckles 5 integral therewith, thus comprising one leaf of a hinge of the 60 door.

6 designates the other leaf of the hinge, the same being secured to the adjacent wall of the foredoor by bolts and nuts, or other suitable means, and so firmly held in position, in the present case near the upper end of the port 3, said leaf consisting of a plate of metal or other suitable material bent on itself and having its bend formed with the series of knuckles 7 integral therewith and placed alternately with the series of knuckles 5, the two series of knuckles having passed through them the pintle 8 thus completing the hinge of the door, and so the latter may be raised and lowered to uncover and cover 70 the port 3, as the case may be, for the purpose hereinbefore stated.

To the inner face of the door 4 is secured the ear 9 to which is pivotally connected the toothed or ratcheted-operating lever or bar 10 which passes through the port 3 towards the chauffeur or driver, and has on its inner end the handle 11 which is within reach of the same so that the door may be conveniently operated.

Connected with the inner side of the foredoor 2 and depending therefrom into the port or opening 3 in the former is the hanger 12 formed of an arm in whose lower portion is the slot 13 through which passes the operating bar 10, the lower wall 14 of said slot being adapted to receive either of the teeth of said bar and so retain the door in the position in which it has been placed. The bolt that secures the arm in position 95 on the foredoor is adapted to pass also through the leaf 6 and so assists in securing the latter to said foredoor said bolt thus being a common fastening for the arm 12 to the leaf and for the latter to the wall 100 of the foredoor.

Connected with the axis of the bar 10 and having its ends bearing against the latter and the door 4 is the spring 15 which serves to hold said bar in engagement with the 105 hanger 12 and prevent improper disconnection thereof.

The slot 13 is sufficiently long to permit the bar 10 to be raised therein when the tooth of the latter clears the lower wall of 110 said slot and so the bar may be pushed in or pulled out by the chauffeur or driver, where-

by the door may be operated after which when the handle 11 is let go, the bar drops and is forced by the action of the spring 15 into engagement with the hanger 5 and so is locked with the latter.

It will be seen that a frame on the wall around the port or opening 3 is eliminated, thus simplifying and reducing the expense of an article of the kind, and as the device 10 is unitary it is easy of installation since all that is necessary is to secure the leaf 6 to a wall of the port 3, which latter may be readily formed in an automobile, if not already existing there.

15 Having thus described my invention what I claim as new and desire to secure by Letters Patent, is:—

1. A ventilator for a vehicle comprising a unitary article composed of a door having thereon a knuckle, a leaf having thereon a knuckle, a pintle in the two sets of knuckles, a depending hanger having therein a slot, and a lever connected pivotally with said door and adapted to pass freely through 25 said slot in the hanger and having means

to be interlocked with the wall of said slot, said leaf and hanger being attachable to a wall of the vehicle by common fastening means.

2. A door for the ventilating port of an automobile having thereon a series of knuckles, a leaf formed of a plate doubled on itself having on the bend of its two members a series of knuckles which alternate with those of the door, a pintle in the two 35 series, means being provided on said leaf for attaching it to a wall of said port, a hanger connected with the two members of the doubled leaf by means common to both the hanger and doubled leaf, the same having therein a slot, and a lever pivotally connected with said door and adapted to pass freely through said slot and having means adapted to be interlocked with a wall of said slot.
